TWO-WAY CREEP CHECK

Robert T. Woodings, Oakmont, Pa., assignor to
Woodings-Verona Tool Works, Verona, Pa., a
corporation of Pennsylvania

Application June 27, 1941, Serial No. 400,008

8 Claims. (Cl. 238—329)

This invention relates to creep checks for railroad rails, and more particularly to those for single track systems where trains travel in both directions over the same rails.

The ordinary creep check is clamped to a rail base in engagement with that side of the tie from which the rail tends to move across the tie as a train travels over the rail. In two-track systems where all of the trains on one track travel in the same direction, the creep checks are all placed on the same side of the ties because the rails try to creep in only one direction. When only one track is used and trains must travel in both directions over it, it is necessary to restrain the rails from creeping in either direction. In such cases where separate rail anchors are placed on both sides of the ties, the anchors tend to work away from the ties until the rails can creep a considerable distance without being restrained by the anchors.

It is among the objects of this invention to provide a two-way creep check which is easily applied to a rail, which is simple and inexpensive in construction, in which the rail anchors are prevented from working away from the tie, and which is adjustable for use with ties of different widths.

In accordance with this invention a rail anchor of any suitable form is fastened to a rail on each side of a tie in engagement, or substantially so, with the tie. These anchors are tied together by a separate cross bar detachably connected thereto, whereby the anchors are prevented from working away from the tie. The cross bar preferably is so formed that it can be used with ties of different widths. For this purpose the bar most suitably is provided at its ends with transverse shoulders which engage the outer sides of the anchors to hold the anchors in place, one end of the bar having a plurality of these shoulders spaced lengthwise of the bar so that the anchor at that end can be held against the tie regardless of the width of the tie.

The preferred embodiment of the invention is illustrated in the accompanying drawing in which Fig. 1 is a perspective view of my two-way creep check applied to a rail mounted on a tie; and Fig. 2 is a reduced perspective view of the bar that connects the rail anchors.

Referring to Fig. 1 of the drawing, a railroad rail 1 is mounted on a conventional tie-plate 2 provided at the sides of the rail seat with spike holes through which spikes 3 are driven for holding the rail and tie-plate down on the supporting cross tie 4. To restrain the rail from creep-

ing longitudinally in either direction across the tie-plate and tie, a rail anchor 6 is connected to the rail base at each side of the tie and substantially in engagement with it. This anchor may

5 take various forms, but preferably is the one-piece clamping type formed from a resilient metal bar bent to form bearing areas that engage the top and bottom of each rail flange so that the anchor will tightly grip the rail. It is provided 10 at one end with a reverse bend or loop 7 that is driven over the marginal portion of one rail base flange, and at the opposite end with an upwardly extending notched portion 8 that snaps over the edge of the opposite rail base flange.

15 It is a feature of this invention that the anchors are prevented from working away from the tie as trains travel back and forth over the rail. Accordingly, the two anchors are connected together by a separate straight metal bar 9 that 20 preferably rests on top of the rail base flange and extends along its marginal portion and projects beyond the sides of the tie. The loops 7 at the ends of the rail anchors open wide enough to permit them to be driven up over the projecting 25 ends of the bar which is thereby clamped to the rail, and a pair of spikes 3 engage the top of the bar for pressing the rail down onto the tie plate. To enable the bar to hold the anchors close to the sides of the tie, its opposite ends are 30 provided with transverse shoulders 11 and 12 that engage the outer sides of the anchor loops 7. The bar is of such length that these shoulders are spaced apart just far enough to hold the rail anchors substantially in engagement with the 35 sides of a standard wide tie, such as a ten inch tie.

Another feature of this invention is that this two-way creep check can be used just as satisfactorily with narrower ties. To provide for 40 this, at least one end of the bar is provided with one or more transverse shoulders 13 and 14 spaced apart longitudinally of the bar distances corresponding to the usual standard variations in widths of ties. Thus, the distance between 45 the innermost shoulder 14 and shoulder 12 at the opposite end may be such as to be used when an eight inch tie is employed, while the other shoulder 13 may be used with a nine inch tie. Consequently, the same pair of anchors and the same 50 connecting bar can be used with ties of various widths, thereby facilitating mass production of these creep checks.

The shoulders in the bar are formed preferably by notching the bar to provide inwardly facing substantially vertical surfaces. These notches

may take various forms, those shown in the drawing having outwardly and downwardly inclined bottom surfaces 16 at the outer ends of which the shoulders are formed. In such a case the lower surfaces of the overlying upper ends of the anchors should be inclined correspondingly to fit flat against surfaces 16.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A two-way creep check for a rail mounted on a cross tie, said creep check comprising a pair of rail anchors adapted to be fastened to the rail and formed for independently holding themselves thereon at both sides of the tie, and a separate bar provided at its ends with shoulders adapted to engage said anchors above the tie to hold them close to the sides of the tie.

2. A two-way creep check for a rail mounted on a cross tie, said creep check comprising a pair of one-piece resilient rail anchors adapted to be clamped to the rail by their resiliency and to engage both sides of the tie, and a separate bar adapted to engage said anchors above the tie and formed for holding them close to the sides of ties of different widths.

3. A two-way creep check for a rail mounted on a tie-plate on a cross tie, said creep check comprising a pair of one-piece resilient rail anchors adapted to be clamped to the rail by their resiliency and to engage both sides of the tie, and a separate bar adapted to be clamped to the rail by said anchors, the ends of the bar being provided with shoulders for engaging the outer sides of the anchors to hold the anchors close to the sides of the tie.

4. A two-way creep check for a rail mounted on a tie-plate on a cross tie, said creep check comprising a pair of rail anchors provided with clamping jaws adapted to grip the rail base

flanges at both sides of the tie, and a separate bar adapted to be clamped to the rail by said jaws, the ends of the bar being provided with notches for receiving end portions of the jaws to hold the anchors close to the sides of the tie.

5. A two-way creep check for a rail mounted on a tie-plate on a cross tie, said creep check comprising a pair of rail anchors adapted to be fastened to the rail and to engage both sides of the tie, and a separate bar adapted to be clamped to the rail by said anchors, the ends of the bar being provided with transverse shoulders for engaging the outer sides of the anchors to hold the anchors close to the sides of the tie, and one end of the bar having a plurality of said shoulders spaced longitudinally thereof whereby to hold the anchor at that end close to the tie regardless of the width of the tie.

6. The combination with a rail having a base flange mounted on a tie-plate on a cross tie, of a rail anchor fastened to the rail at each side of the tie and substantially engaging the tie, a bar clamped to the top of the rail base flange by said anchors and engaging only said top, said bar being formed to hold the anchors close to the tie, and means overlying said bar between said anchors for fastening the rail to the tie.

7. In a two-way creep check for a rail mounted on a cross tie, a bar adapted to be clamped to the rail by rail anchors disposed on opposite sides of the tie, said bar being formed to engage only the top of the rail base flange and being provided with a transverse shoulder at each end for engaging the outer sides of said anchors to hold them substantially in engagement with the sides of the tie.

8. In a two-way creep check for a rail mounted on a cross tie, a bar of rectangular cross section adapted to be clamped to the top only of the rail base flange by rail anchors disposed on opposite sides of the tie, said bar being provided with a single transverse shoulder at one end and a plurality of transverse shoulders at the opposite end for engaging the outer sides of said anchors to hold them substantially in engagement with the sides of the tie.

ROBERT T. WOODINGS.
